UNITED STATES PATENT OFFICE

106,895

DESIGN FOR A DRESS

Margaret Michelson, New York, N. Y.

Application October 6, 1937, Serial No. 71,992

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The sleeves and yoke portions of the dress are sequin studded, as shown.

I claim:

The ornamental design for a dress, substantially as shown, and described.

MARGARET MICHELSON.
